US00D913289S

(12) **United States Design Patent** (10) **Patent No.:** **US D913,289 S**
(45) **Date of Patent:** **** Mar. 16, 2021**

(54) **CROWN FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Erik Geddes Pieter De Jong**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Sameer Pandya**, Sunnyvale, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/755,240**

(22) Filed: **Oct. 19, 2020**

Related U.S. Application Data

(63) Continuation of application No. 29/661,789, filed on Aug. 30, 2018, now Pat. No. Des. 899,426.

(57) **CLAIM**

The ornamental design for a crown for an electronic device, as shown and described.

DESCRIPTION

FIG. 1 is a top front perspective view of a crown for an electronic device showing the claimed design; FIG. 2 is a top rear perspective view thereof

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the crown for an electronic device that form no part of the claimed design.

1 Claim, 8 Drawing Sheets
